UNITED STATES PATENT OFFICE.

WILLIAM PHILLIPS, OF NEW YORK, N. Y., ASSIGNOR TO EUREKA RADIO AND PHONO PARTS CO., A CORPORATION OF NEW YORK.

COMBINED PHONOGRAPHIC AND TELEPHONIC APPARATUS.

Application filed January 29, 1924. Serial No. 689,217.

To all whom it may concern:

Be it known that I, WILLIAM PHILLIPS, a citizen of the United States, and resident of New York city, in the county of New York and State of New York, have invented certain new and useful Improvements in Combined Phonographic and Telephonic Apparatus, of which the following is a specification.

10 My present invention relates to sound reproducers and more particularly to apparatus for use alternatively as a phonograph or as an amplifying telephone receiver, the latter application more especially for amateur radio purposes.

The invention relates to a construction of the general type described and claimed in my copending application, Serial No. 674, 615, filed November 14, 1923, and as to certain features thereof is an improvement thereover.

It is an object of the invention to provide an apparatus of the above type which shall eliminate the need for mounting or dismounting the phonograph sound box or the telephone receiver with respect to the tone arm in order to change over from phonograph to radio operation and vice versa, and which shall yet be capable of use at will, either as a phonograph for playing a record, or as an amplifying telephone receiver or loud speaker operable from a radio receiving set.

It is another object to provide an apparatus of the above type, the operation of which will be satisfactory either as a phonograph or as an amplifying telephone receiver, and which may, moreover, be employed to produce novel effects for simultaneous reproduction of phonograph records, synchronized, if desired, with complementary telephonically transmitted messages or selections.

The invention has a preferred application to the substantially conventional phonograph, the tone arm only of which is modified to provide a double inlet, at one of which is connected the usual sound box having a diaphragm actuated from the usual stylus, and to the other of which is attached a telephone receiver. In the preferred embodiment, the entire weight of the tone arm

together with that of the sound box and of the telephone receiver carried thereon, is supported at the pivoted or amplifier end, so 55 that the weight of the telephone receiver which may be permanently retained on the tone arm shall not increase the pressure of the sound box stylus upon the record groove.

In operating an apparatus of the type 60 shown in my copending application, for radio receiving, I have found that if the stylus is not in place, the vibrations from the radio receiver may effect chattering of the sound box. To obviate this, I have 65 according to the present invention, provided means for automatically interrupting sound communication between the radio receiver and the sound box, when the latter is in inoperative or non-record playing relation. 70 In the preferred embodiment, the support arm of the sound box extends transversely across the tone arm and is provided with a valve, which allows free communication therefrom to the tone arm, when the sound 75 box is in record playing position, but closes communication to the tone arm when the sound box is elevated to inoperative or idle position.

The branch tube for mounting the radio 80 receiver is preferably at the delivery side of the valve, so that the valve when closed, will in no way interrupt communication between the radio receiver and the tone arm. Preferably the radio receiver supporting 85 branch of the tone arm extends at an acute angle to the length of the tone arm to direct the vibrations lengthwise of the tone arm and to avoid sharp angular deflections of the sound wave.

Since in my construction, the radio receiver is permanently left on the apparatus regardless whether the latter is used for phonographic or radio purposes, I prefer to affix the electrical conductors leading to the 90 receiver at intervals lengthwise of the tone arm and near the pivot end thereof, where they will be unlikely to become caught and where they will be effectively concealed.

In the accompanying drawings in which 100 are shown one or more of various possible embodiments of the several features of this invention,

Fig. 1 is a fragmentary elevation partly

in section, of a preferred embodiment of the invention,

Fig. 2 is a fragmentary plan view on a larger scale and partly in section of a tone arm embodying my invention,

Fig. 3 is a fragmentary sectional view taken along the line 3—3 of Fig. 2, showing the valve in closed position.

Fig. 4 is a view similar to Fig. 3, showing the valve in open position.

Fig. 5 is a detail view showing the application of a common form of telephone receiver attachment designed for phonograph application, and,

Fig. 6 is a fragmentary detail indicating the closure of the radio receiver nipple by a special cap.

Referring now to the drawings, I have shown a phonograph cabinet 10, supporting a phonograph record turn table 11 to be rotated by the usual spring or electric motor (not shown) mounted on the lower surface of motor board 12. Within the cabinet is the usual amplifier 13 to the upper end of which is connected the tone arm 14. In the preferred embodiment, the tone arm is pivotally mounted upon a metal support spider 15 secured as by screws 16 to the motor board 12. The spider 15 has a thrust bearing 17 for a cooperating thrust bearing member 18 at the lower surface of a spider 19 in the tone arm. A pin 20 longitudinally through spider 19 and secured thereto, has a bearing in a corresponding elongated hub 21 in the support spider 15 and constitutes the pivot mount, which permits the rotary movement of the tone arm across the turn table for playing a record. The tone arm is illustratively shown of the taper form, the amplifier end of which telescopes into the hub 22 of support spider 15 with small clearance 23 therebetween. The tone arm has the usual lateral inlet 24 upon which the usual S-shaped sound box support 25 is attached by screw 26 which permits pivotal displacement of the neck 25 with sound box 27, to sustain the latter disengaged from the record or turn table when out of use. The sound box which includes the usual annular diaphragm 28 of mica or equivalent material clamped in place at its rim and actuated from the stylus 29, has a neck 30 telescoped with respect to the outer end of support arm 25.

In the preferred embodiment, the usual tone arm described, is cast with an integral branch 32 extending obliquely forward at an acute angle to the length of the tone arm and from near the extreme or free end thereof, and preferably, as shown, to somewhat beyond the end of the main length of the tone arm.

The receiver shown in Fig. 2 is substantially of the usual head-set type and includes a casing 31 which may be of vulcanite with-

in which is mounted the electromagnetic telephone coil C, the terminals of which are shown at 33. The magnetic diaphragm 34 is confined by a cap 35 threaded at 36 upon the casing and formed, in the embodiment shown, with an integral threaded socket 37 to be threaded over the nipple 38 at the outer end of branch 32. The end of socket 37 preferably forms a metal to metal bottoming engagement with the shoulder 38 at the base of the nipple.

Preferably the nipple 38 is also adapted alternatively to mount the familiar phonograph loud speaker attachment, constituting an article of commerce intended to be substituted for the sound box on an ordinary tone arm, in order to adapt a phonograph as a radio loud speaker. For this application, as will be seen in Fig. 5, the loud speaker attachment neck 40, which is provided with the usual rubber bushing 41 is simply telescoped over the threads of nipple 38, the inner face of bushing 41 snugly engaging said threads, to form an adequate sound-tight connection.

Thus, my tone arm may be used either with a head set receiver that has a special socket threaded exteriorly over nipple 38, or with the usual loud speaker phonograph attachment, with the usual rubber bushing 41 which is telescoped over said nipple.

I have found in a construction of the general type invented by me, in which the tone arm carries concurrently both a phonograph sound box and a radio receiver, both in communication with the length of the tone arm and with each other, that in the event the stylus clamping screw 8 of the sound box is loose when the apparatus is used for radio purposes, the vibrations from the receiver 31 may cause annoying chatter at the sound box. This I avoid by a simple construction, whereby when the sound box is elevated to idle or inoperative position, communication therewith from the radio receiver is automatically interrupted. For this purpose, the neck 44 of the sound box support arm 25, extends transversely across the width of the tone arm, and has not only a bearing in tone arm branch 24, but an auxiliary bearing 42 in the opposite side of the tone arm. The neck 44 is held in place within its bearings, as shown, by the stud of screw 26, which is threaded into branch 24 and extends into a peripheral groove 43 about neck 44. The neck 44 is cut-away as shown at 45 to provide a passage preferably registering with the bore of the tone arm 14 when the sound box is placed in record playing position, while in the position best shown in Fig. 2, when the sound box is elevated to ineffective or inoperative position, the pivot end 44 of arm 25 closes communication between the sound box and the tone arm, as shown.

130

The branch 32 for the radio receiver communicates with the main length 14 of the tone arm adjacent but at the delivery side of the valve 45, so that whether the valve is 5 opened or closed, the sound transmitting passage from the radio receiver to and through the tone arm will neither be impaired nor interrupted.

It will, of course, be apparent that a 10 telescoping friction fit mount of the telephone receiver may be substituted for the threaded attachment shown in Figs. 2 and 3, although the threaded mount is preferred. It will also be understood that although the metal 15 to metal engagement shown in Fig. 2 of the drawings is sufficiently tight for ordinary use, compressible washers or gaskets may be employed in the well understood manner, to assure a sound tight connection.

20 The sound box and the telephone receiver both remaining affixed to the tone arm at all times, whether the apparatus is used as a phonograph or as a radio loud speaker, the connecting joint for the sound box is 25 not likely to wear loose as in constructions in which the sound box must be slipped out and the loud speaker attachment slipped onto the tone arm whenever the phonograph is to be used for radio reception, and vice 30 versa, to restore the apparatus for phonograph use. Moreover, the likelihood of mislaying or injuring the separated sound box or receiver, or of scratching furniture therewith, is wholly obviated in my construction, 35 in which there is no occasion to remove from the tone arm either the sound box or the telephone receiver.

The apparatus is used as a phonograph in the ordinary manner, it being noted that 40 since the entire weight of the tone arm and associated apparatus is supported at the thrust bearing 17, the weight of the telephone receiver at the outer end of the tone arm will not add to the pressure of the stylus 45 against the record R. The telephone receiver casing 31, moreover, affords a convenient handle for manipulating the tone arm in starting a record.

50 When the sound box stylus is placed in contact with the record groove, the valve is automatically opened to establish communication between the sound box, and the tone arm. The main sweep of the sound waves will advance forward through the tone arm, 55 although some vibration may be transmitted rearward through the branch 32 to affect the radio receiver diaphragm. By this joint operation of both the sound box and telephone receiver, the quality and clearness of the operation as a phonograph is distinctly improved, for reasons which I will not attempt to explain.

When the record selection is completed, 60 the sound box may be thrown back to inoperative position by pivoting about its

mount 44 without interference with the telephone receiver 31.

In that position, the radio receiving apparatus may be set up without any need for 70 touching any part of the apparatus shown in the drawings. The vibrations impressed on the magnetic diaphragm 34 are delivered through the tone arm branch 32 and through the length of the tone arm 14 and are magnified in the amplifier 13. Since the valve 75 45 is closed when the sound box is in the elevated position, no vibrations from the telephone receiver are transmitted to the sound box and the chattering which might occur therein in radio operation, particularly if 80 the screws were loose is thus obviated.

My apparatus is also susceptible of a use 85 which I believe is broadly new, for conjoint or simultaneous phonographic and telephonic or radio amplification through the phonograph amplifier. A phonograph record might for instance, be played while the same selection is received in synchronism therewith upon the radio set, both the record reproduction and the telephonically transmitted vibrations being projected through the phonograph amplifier. In another specific application, a vocal selection received on the radio set might be amplified by the phonograph in synchronism with the corresponding musical accompaniment played on the record.

95 My invention is also an instrumentality for a distinctly novel entertainment. A phonograph musical record without vocal 100 accompaniment may be played, for instance, and thereupon the entertainer may play the same record which now appears to include a vocal accompaniment, the latter produced by an assistant in an adjoining room who now sings the accompaniment into a telephone transmitter which is connected in a wired telephone circuit with the receiver 105 on the telephone.

110 Other interesting, surprising or ludicrous effects will readily suggest themselves.

A further use of the device is for recording on an appropriate blank record, selections transmitted over the radio apparatus. For this purpose, the radio apparatus being 115 connected and the sound box being lowered, so that its stylus rests upon the blank record, as indicated in Fig. 1, the sound vibrations impressed upon the radio receiver diaphragm 34 are transmitted through the device and impressed upon the sound box diaphragm 28, the valve 45 being, of course, open when the sound box is in operative 120 position as described, so that the stylus will act to cut the record, to imprint thereon the radio transmitted selection. In this latter operation, it is preferred to close the doors D or other passage at the outer end of the amplifier, so that the vibrations from the 125 radio receiver passed into the tone arm, will 130

be confined and effectively impressed upon the sound box diaphragm.

As the radio receiver can be permanently left upon the tone arm and need not be removed and replaced by the sound box, as in a construction in which one apparatus must be substituted for the other, the electrical conductors 50 leading to the radio receiver need not extend loose, where they are likely to be in the way and become tangled, but, as best shown in the drawings, these conductors are extended longitudinally of the tone arm and preferably below the same through appropriate eyes 51 that may be screwed into the tone arm, the conductors extending thence out to the receiving set. Thus, it will be seen, that in the use of the apparatus as a phonograph, the tone arm in its pivotal movement will in no way be hampered by the electrical conductor 50, and the end of the latter at the pivot end of tone arm 14, partakes of only small movements rendering unnecessary great excess of length of wire between the phonograph apparatus and the radio receiving set.

If it is desired to use my special tone arm construction without radio attachment, a cap such as shown at C in Fig. 6 may be threaded over the nipple end of the branch 32, and the phonograph will operate as with an ordinary tone arm.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

Having thus described my invention, what I claim as new and desire to secure by Letters-Patent of the United States is:—

1. A combined phonograph and amplifying telephone receiver comprising an amplifier, a pivotally mounted tone arm communicating therewith, a sound box unit mounted upon said tone arm for coaction with a phonograph record, means sustaining the entire weight of said tone arm independently of said sound box and a telephone receiver fixed to said tone arm near said sound box, to communicate the vibrations impressed thereon through said tone arm.

2. In a combined phonograph and radio receiving apparatus, in combination, a tone arm having a pair of nipples, a sound box pivotally mounted at one of said nipples,

and a telephone receiver mounted at the other of said nipples, said sound box and receiver in sound vibration-communicating relation with the tone arm, and means for automatically interrupting communication between said telephone receiver and said sound box, when the latter is moved to idle position, thereby affording direct communication from the telephone receiver to and through the tone arm.

3. In a combined phonograph and radio receiving apparatus, in combination, a motor board, a tone arm mounted thereon, a nipple protruding laterally from the tone arm, a sound box having a support arm pivotally mounted in said lateral nipple, a valve member under the control of said support arm and extending transversely in the tone arm, and in axial alignment with said nipple to substantially close communication between said neck and said tone arm when the sound box is in elevated or inoperative position, and a second nipple protruding from said tone arm, said second nipple being adapted for mounting a radio receiver rigidly thereon and in sound tight relation thereto, above said motor board, whereby when the apparatus is used for radio reception, and the sound box is in elevated or inoperative position, communication will be interrupted between the radio receiver and the sound box.

4. In apparatus of the character described, in combination, a tone arm having an integral branch extending obliquely forward from near the forward or free end thereof, said branch having means at the outer end thereof for supporting a telephone receiver in sound-tight relation therewith, and a second nipple extending substantially at right angles to the length of the tone arm at the extreme forward end thereof and in a horizontal plane, said nipple constructed to mount a phonograph sound box.

5. In apparatus of the character described, in combination, a tone arm having a pivoted support end, an integral nipple extending horizontally substantially at right angles to the tone arm from near the extreme or free end thereof, a sound box having a support arm pivotally mounted in said nipple, said tone arm having a second nipple integral therewith, extending at an acute angle to the main length of said tone arm, obliquely from a part of the tone arm between the pivot end thereof and said first nipple forward to beyond the free end of the main length of said tone arm, and a radio receiver fixed in sound-tight relation upon the free end of said second nipple.

6. A tone arm for combined phonograph and radio receiving apparatus having a pair of support tubes integral therewith and extending from opposite sides thereof, a support arm pivotally mounted in one of said

support tubes, a sound box neck telescoped with respect to the outer end of said support arm, the other said support tube being threaded at its outer end, the outer diameter of said threads being substantially equal to the diameter of said sound box neck, whereby a conventional radio receiver intended

to be substituted for a sound box on an ordinary tone arm, may be applied at the threaded end of said second support tube. 10

Signed at New York in the county of New York and State of New York this 28th day of January A. D. 1924.

WILLIAM PHILLIPS.
